STORAGE BATTERY HOLD-DOWN BRACKET

Max Antritter, Mile Hill Road, Boylston, Mass.

Filed Mar. 8, 1963, Ser. No. 73,880

Term of patent 14 years

(Cl. D54—13)

Fig. 1

Fig. 3

Fig. 2

Fig. 5

Fig. 4

FIGURE 1 is a side elevational view of a storage battery hold-down bracket showing my new design;

FIG. 2 is a top plan view thereof;

FIG. 3 is a section taken on line 3—3 of FIG. 2;

FIG. 4 is an elevational view from the rear end thereof; and

FIG. 5 is a section taken on line 5—5 of FIG. 4.

I claim:

The ornamental design for a storage battery hold-down bracket, as shown.
